UNITED STATES PATENT OFFICE.

HENRY F. WEST, OF GLOUCESTER CITY, NEW JERSEY.

CAR-AXLE LUBRICATOR.

SPECIFICATION forming part of Letters Patent No. 396,125, dated January 15, 1889.

Application filed April 10, 1888. Serial No. 270,190. (No model.)

To all whom it may concern:

Be it known that I, HENRY F. WEST, a citizen of the United States, residing at Gloucester City, in the county of Camden and State of New Jersey, have invented certain new and useful Improvements in Car-Axle Lubricators, of which the following is a specification.

The principal object of my invention is to provide simple devices and means for lifting the lubricant or oil from a reservoir in the car-axle box and distributing uniformly the same over the surface of the journal, and thereby dispensing with all waste, wicking, or other analogous material heretofore packed into axle-boxes to cause lubrication of the journal to be effected by capillary attraction.

My invention consists in mounting on the journal of the axle one or more cylindriform devices, which is or are rotated thereby for lifting or elevating the lubricant or oil to allow of its discharge through diverging channels formed in a saddle suitably supported in position on the journal, and thereby causing the lubricant or oil to be distributed uniformly over the surface of the journal of the car-wheel axle.

My invention further consists of certain details of construction and combinations of parts, to be hereinafter fully described.

The nature of my invention will be more fully understood by reference to the accompanying drawings, forming part hereof, wherein my invention has been illustrated in forms found practically efficient, and in which—

Figure 1 is a longitudinal section through a car-axle box with the lubricant contained in the bottom thereof and with my improved cylindriform lifting device and saddle shown in application mounted on the journal. Fig. 2 is a cross-sectional view on the line $x-x$ of Fig. 1. Fig. 3 is a view in perspective, on a small scale, of one form of my improved saddle or journal-block, showing the two channels therein diverging from a point central at one end and terminating in the opposite end in the walls thereof. Fig. 4 is a longitudinal section through a car-axle box, showing two of my improved cylindriform lifting devices in application and a slightly-modified form of saddle mounted on the journal. Fig. 5 is a cross-sectional view on the lines $y-y$ and

$z-z$ of Fig. 4; and Fig. 6 is a view in perspective, on a small scale, of said modified form of saddle or journal-block, showing the channels therein diverging from a central point at each end to a point central to the bottom of the saddle or block.

Referring to the drawings for a further description of my invention, A is a car-axle box, of any suitable construction.

B is a lid or cover hinged to the top plate of the box, this lid B being provided with a catch, b, or other device, cast with the lid or cover for raising the same to admit the lubricant or oil into the reservoir D in the bottom of the box.

E is the journal of the axle, having a shoulder or rim, e, on its front extremity, whereon is mounted the lubricant-lifting device, to be hereinafter fully described.

H is a saddle or journal-block, made of brass or other suitable material, with a rear shoulder or projection, h^3 . The bottom of this block or saddle is hollowed out or formed concave, and in the surface thereof are formed two diverging channels, h and h' , which extend from end to end of the block, as shown in Fig. 3. The use of a saddle provided with such diverging channels h and h' has this important advantage, that the oil or lubricant from the well beneath, elevated by means of the lifting and discharging device K, is not only deposited onto the journal E, but it is also uniformly distributed through the channels of the saddle over the entire surface thereof, and the heating up of the same due to frictional contact of the saddle therewith entirely avoided. In the use of saddles as heretofore constructed—mounted on journals, for instance, with oblique grooves formed therein—it is only possible to partially lubricate the same, and hence as the solid portions of such saddles are in frictional contact with the journal the constant heating up of the same has been a natural consequence simply because of the fact that the lubricant was not uniformly distributed over the surface thereof, as is the case in the use of my improved saddle, as shown and described. This saddle H is mounted on the journal E, and held in position thereon by means of a bearing-plate, I, which engages with the shoulder or projec-

tion h^3 of the saddle and the projection a of the top plate, a' , of the axle-box A, thereby preventing all lateral wobbling of the saddle.

On the shoulder or annular rim e of the journal E is mounted a cylindriform lubricant lifting and discharging device, K, which is held to place thereon by means of one or more set-screws, l . This lifting and discharging device K, made of cast-iron or other suitable material, consists of a hollow cylinder, k , with a central depression or recess, k' , which permits of the mounting of the device readily onto the shoulder e of the journal, as shown, for instance, in Fig. 1, and the securing of the same in position thereon by means of set-screws l .

Within the hollow cylinder k , preferably formed integral therewith, are curved channels k^2 and k^3 , which are separated from each other by partition-walls k^4 . In the circumferential surface or wall of this hollow cylinder are provided apertures or inlets k^5 , which are arranged so that the lubricant or oil forced in through these inlets will be carried upward by the rotation of the device by the axle through the channels k^2 or k^3 , and discharged through apertures or outlets k^6 in the opposite surface of the hollow cylinder k at the top of the journal into and through the diverging channels h and h' in the saddle or journal-block, and thereby distributed uniformly over the surface of the journal.

It will be observed by reference to Fig. 2 that the lifting and discharging device K is constructed so that the lubricant carried upward and discharged into the channeled saddle or block H, and distributed therethrough uniformly over the surface of the journal of the axle, may perform its functions in either direction of rotation of the axle which actuates said device.

With special reference, now, to Fig. 4, which illustrates a modified arrangement of my invention, A is the axle-box, and B the lid or cover hinged to the top plate of the box, this lid or cover being provided with a catch or other suitable device, b , cast therewith, for permitting of the elevation of said lid to cause the lubricant or oil to be charged into the reservoir D in the bottom of the box A.

E is the journal with a shoulder or rim, e , on its front extremity.

H is the saddle or journal-block, made of brass or other suitable material, with a rear shoulder or projection, h^3 , the central portion of this block or saddle being hollowed out or formed concave, and in the surface thereof channels h and h' are formed, which diverge in opposite directions from a central point at each extremity to a central point in the sides or surfaces of the concave portion of the block, whereby the oil or lubricant received at each end from the lubricant lifting and discharging devices may be distributed uniformly over the surface of the journal, as will be presently more particularly explained. This saddle H is mounted on the journal E, and held

in position thereon by means of a bearing-plate, I, which engages with the shoulder or projection h^3 of the saddle, and the projection a of the top plate, a' , of the axle-box A, thereby preventing any wobbling laterally or otherwise of the saddle while in position. On the shoulder or annular rim e of the journal E is loosely mounted, in this instance, the cylindriform lifting and discharging device K, constructed in the manner hereinbefore fully described. This device, loosely mounted on the rim e of the journal E, has two or more openings formed in the surface thereof for permitting of the insertion of bolts.

Secured into the head of the journal in any suitable manner are two or more bolts, l , having one or both extremities thereof threaded, and these bolts, passed through said openings in the device K, have mounted thereon coiled or helical springs l' and nuts l'' , whereby the device K may be always kept in proper position snugly up against the end extremity of the channeled saddle H, with the avoidance of all squeaking, but principally compensating for all wear that may take place between the device and the saddle by reason of the contact of one with the other.

On the axle of the journal E is mounted a similar lubricant lifting and discharging device, K, with this exception, that instead of a central recess or depression, k , being formed therein an annular opening extends through the hollow cylindriform device K, as shown in Fig. 4, and which device, loosely mounted on the axle, is held in position up against the end extremity of the saddle H by means of a collar, m , mounted on said axle, and held rigidly thereon by means of tightening-screws n . Into the surface of the collar m are secured two or more bolts, o , having coiled around them springs o' , the opposite free extremities of which bolts play freely in openings provided in the surface of the cylindriform device K, whereby it is rendered possible to readily adjust the position of said device K so that it will always rest snugly up against the end extremity of the saddle H, for the performance of its functions of lifting the lubricant by the rotation of the axle and discharging the same through the channels of the saddle, and thereby uniformly lubricating or oiling the journal of the axle.

I am aware that various means have heretofore been used for effecting the lubrication of ear-axle journals, and therefore I do not wish to be understood as claiming, broadly, devices for so doing, but simply the devices and means constructed, arranged, and operating in the manner hereinbefore explained.

Having thus described the nature and objects of my invention, what I claim as new, and desire to secure by Letters Patent, is—

1. The lubricant lifting and discharging device K, in combination with the journal E of the axle, arranged as described, and for the purposes set forth.

2. The lubricant lifting and discharging de-

vice K, in combination with the journal E of the axle and the saddle H, having diverging channels formed in the body thereof, all arranged as described, and for the purposes set forth.

3. In a car-axle box, the combination, with the journal E, of the axle and the lubricant lifting and discharging device K, mounted on said journal, means, as described, for holding the same in position thereon, and the saddle H, provided with diverging channels in the body thereof, whereby the lubricant elevated by said device may be uniformly distributed over the surface of the journal, all arranged as described, and for the purposes set forth.

4. In a car-axle box, the combination of the journal E of the axle, the lubricant lifting

and discharging devices K, mounted on said journal, means, as described, for adjustably maintaining said devices in position on said journal, and the saddle H, having diverging channels in the body thereof, whereby the lubricant lifted by said devices may be distributed uniformly over the surface of the journal in both directions, as shown and described.

In witness that I claim the foregoing as my invention I have hereunto set my signature in the presence of two subscribing witnesses.

HENRY F. WEST.
